(21) Appl. No.: **29/219,471**

(57) **CLAIM**

(22) Filed: **Dec. 20, 2004**

The ornamental design for a breather to clean and dehumidify air, as shown and described.

(51) **LOC (8) Cl.** 23-04

DESCRIPTION

(52) **U.S. Cl.** **D23/359**

FIG. 1 is a perspective view of a breather to clean and dehumidify air showing my new design invention;

(58) **Field of Classification Search** D23/359,

FIG. 2 is a right side elevation view thereof;

D23/360, 356; 96/108, 146, 151

FIG. 3 is a front elevation view thereof;

See application file for complete search history.

FIG. 4 is a bottom plan view thereof;

(56) **References Cited**

FIG. 5 is a top plan view thereof;

U.S. PATENT DOCUMENTS

FIG. 6 is a rear elevation view thereof; and,
